ABSTRACT OF THE DISCLOSURE

A machine provided with lining bricks which have a face exposed to wear and side and end surfaces which equal the thickness of the bricks and are concealed by adjacent bricks, said thickness defining surfaces having applied thereto wear indicating means. Said means comprise a right angle triangular design in which one of the right angle edges is perpendicular to the exposed face of the brick and located at a distance from the adjacent parallel edge of the thickness defining surface to which the design is applied, the other of its right angle side edges being coincident with and visible at the exposed face of the brick, both said side edges being equal in length to the thickness of the brick. The length of the visible edge of the triangular design changes progressively as the exposed face becomes worn and at all times equals the thickness of the brick.

This invention relates to means for indicating the degree of wear of lining bricks for ball mills, chutes, conveyors, tanks, separators and other machines in which it is desirable to determine the thickness of lining bricks in use.

This application is a continuation-in-part of our application, Ser. No. 492,818, filed Oct. 4, 1965, and now abandoned.

Ball mills are lined with high strength lining bricks of suitable material, such, for example, as alumina ceramic. Ball mills are used for grinding paints, enamels and other materials which must not be contaminated by contact with metal or other foreign matter. When a ball mill lining becomes excessively worn, the lining bricks are likely to become loose and may fall into the material being ground while the mill is in operation, resulting in damage to both the mill and the material therein.

The main object of this invention is to provide means quickly and easily observable for accurately indicating the degree of wear of lining bricks in ball mills and other machines, and the exact thickness of the remaining worn bricks.

Another object is to provide indicating means for the purpose stated which do not contaminate the materials being treated in the mill or other machines, and do not weaken the lining construction.

In the drawings:

FIG. 1 is an isometric view of a ball mill lining brick which has applied to one of its sides a stencilled triangular design of contrasting color, the drawing being lined for blue merely as an example of contrasting color.

FIG. 2 is a similar view showing the triangular design of contrasting color defined by a saw cut groove.

FIG. 3 is a view similar to FIG. 1 showing a ball mill lining brick which is provided with a recess in one of its sides and a contrasting insert in the recess.

FIG. 4 is a view of the brick shown in FIG. 3 after it has been worn to one-half of its initial thickness.

FIG. 5 is an elevational end view of a lining brick

2

showing a scribed line or indentation on one end surface, the line together with the upper and side edge of the brick defining a triangular design.

FIG. 6 is a top view, broken away, of the brick shown in FIG. 5.

FIG. 7 is an elevational end view of a lining brick showing scribed lines or indentations in the end surface of the brick, which can be located on either end or on either side of the brick, to outline a triangular design.

FIG. 8 is a top view, broken away, of the brick shown in FIG. 7.

FIG. 9 is an elevational perspective view of a ball mill such as shown in U.S. Patent 3,110,448, assigned to the assignee of this application, to which the wear indicating means may be applied.

FIGS. 1-3 of the drawings show a conventional ball mill lining brick, such as are used to line the flat ends of ball mills. The invention may also be applied to bricks which line the cylindrical body of the mill.

20 In that embodiment of the invention shown in FIG. 1, the brick has a top 10, end surface 11, and side 12. A bottom surface, end and side surfaces (not shown), correspond to the surfaces 10, 11 and 12, respectively. A triangular design 13 is stencilled on the side 12 with ink of contrasting color. The drawing has been lined for blue. The preferred design is a right angle triangle 13 which has one of its right angle sides extending vertically of the brick, parallel to the end 11 and as long as the depth of the brick.

30 The other right angle side of the triangle 13 extends horizontally, coincident with the upper edge of the side 12 where it joins the top 10. The wear indicating bricks may be installed at random in the mill lining. When installed between other bricks to form a complete lining, and assuming the brick is two inches thick, the upper horizontally extending edge of the triangle will be visible as a contrasting colored line two inches long while the brick is unworn. The visible line of the stencilled design will become progressively shorter as the lining bricks become worn, and the length of the visible line will equal the remaining depth of the brick.

It is possible that stencil inks employed as described in connection with FIG. 1 may "bleed" and spread slightly into the ceramic material adjacent the triangular design.

45 To overcome this possibility, the triangular design may be isolated from the ceramic material adjacent the vertical right angle edge and the hypotenuse of the triangular design. This modification is shown in FIG. 2, where the stencilled triangular design 14 is defined by saw cut grooves 15. The presence of the grooves 15 adjacent two edges of the stencilled triangular design prevents the design from spreading. This arrangement ensures that the visible width of the triangle will give an accurate indication of the depth of the marked brick.

55 FIG. 3 shows another modification of the invention in the form of a colored triangularly shaped insert 16 located in a recess in the side 12 of the lining brick. The insert of contrasting color may be the same ceramic material as the body of the brick. The insert serves the same purpose as the stencilled designs of FIGS. 1 and 2.

FIG. 4 shows an initially two inch thick brick which has become worn to one-half its thickness or depth as indicated at 18, and in which the triangular insert 17 has likewise become worn. The length of the visible edge 19 of the insert 17 is only one inch long when the remaining thickness of the brick is one inch.

The design of FIG. 5 comprises a scribed or indented line 21 which together with the top and side edges of the brick end 11 define the triangular design. Colored cement or other material may be used to fill the indented line 21. The cement which is used for bonding the bricks

in place may be used to fill the depression of the line 21, the different color enabling one to determine the distance at the exposed top of the brick from the indentation 21 to the edge of the side 12, as shown in FIG. 6.

The design of FIG. 7 is similar to that of FIG. 5, except that two scribed lines or indented lines 22 and 23 are used to define the triangular design. The description of the line 21 of FIG. 5 applies also to lines 22 and 23 of FIGS. 7 and 8.

The ball mill shown in FIG. 9 is designated 25 as a whole, and the exposed faces of the bricks have been designated 10. Any one of the several wear indicating means may be applied to the lining bricks, but the right angle triangular design of FIGS. 7 and 8 is preferred. In this embodiment of the invention, the right angle groove 23 is spaced from the parallel edge of the end wall 12, so that the visible distance between the grooves 23 and 22 at the wear surface 10 equals the depth or thickness of the brick at all times. In the form shown in FIGS. 5 and 6, the junction of the edges of wall surfaces 11 and 12 may become worn and then the visible length of the distance between the wall 12 and the groove 21 may not accurately correspond with the remaining thickness of the brick.

Obviously the described wear indicating design could be an equilateral triangle or other shape but the depth of the worn brick would not be as readily or accurately ascertainable as by our preferred indicating means. By using a right angle triangular design, having a right angle side edge perpendicular to the exposed top of the brick and as long as the thickness of the brick, the thickness of the worn brick is easily determined by measuring the length of the visible edge of the design. This is shown by the visible edge 19 of FIG. 4 which is the same length as the thickness indicated by the dimension 18 and was initially the length 20 as shown in FIG. 3. If the same design were turned upside down, the thickness of the worn brick could be figured by subtracting the length of the visible edge of the insert 17 of FIG. 4 from the initial thickness of the brick. However, by placing the stencilled design or the insert in the positions shown in the drawings, the length of the visible edge 17 of the triangle is exactly the same as the remaining thickness of the lining brick and no calculations are required to ascertain the exact thickness of the worn brick.

We have described the wear indicating means as located on one side of a lining brick, but obviously it could be placed on an end surface provided the brick ends are at least as wide as the thickness of the brick and capable of receiving a right angle triangle design having right angle sides as long as the initial thickness of the brick. When the insert form of indicating means, such as shown in FIG. 3, is employed, we prefer to provide the recess in a side

surface of the brick to provide room for the recess and insert.

We claim:

1. In a machine provided with lining bricks having thickness defining surfaces concealed by adjacent bricks, and each brick having a face exposed to wear and an end face extending perpendicular to the exposed face, the improvement which consists of wear indicating means comprising a design which is an area of right angle triangular shape having one of its right angle side edges intersecting and extending perpendicular to the exposed face of the brick outlined by a groove and parallel to and spaced from the adjacent end face of the brick and the other of its right angle side edges coincident with and visible at the exposed face, the third edge of the triangular area being defined by a diagonal line connecting the two right angle side edges and outlined by a groove, each of said right angle side edges being equal in length to the thickness of the brick, the distance at the exposed face of the brick between the grooves defining the perpendicular edge and the diagonal edge of the design being equal to the thickness of the brick at all times.

2. In a machine provided with lining bricks having thickness defining surfaces concealed by adjacent bricks, and each brick having a face exposed to wear and an end face extending perpendicular to the exposed face, the improvement which consists of wear indicating means comprising a design which is an area of right angle triangular shape having one of its right angle side edges intersecting and extending perpendicular to the exposed face of the brick outlined by a line and parallel to and spaced from the adjacent end face of the brick and the other of its right angle side edges coincident with and visible at the exposed face, the third edge of the triangular area being defined by a diagonal line connecting the two right angle side edges, each of said right angle side edges being equal in length to the thickness of the brick, the distance at the exposed face of the brick between the perpendicular edge and the diagonal edge of the design being equal to the thickness of the brick at all times.
